UNITED STATES PATENT OFFICE

CHARLES F. SMITH, OF MILWAUKEE, WISCONSIN, ASSIGNOR TO SMITH ENGINEERING WORKS, OF MILWAUKEE, WISCONSIN, A CORPORATION OF WISCONSIN

FEEDING DEVICE FOR CRUSHERS AND THE LIKE

Application filed July 29, 1926. Serial No. 125,729.

My invention has relation to improvements in feeding devices for crushers.

The primary object of my invention is to provide an automatically operating feeding device adapted alternately to increase and diminish the width of the opening of a supplemental hopper leading to the passage in which the material is crushed.

A further object is to provide a universally mounted feeding device adapted to alternately increase and diminish the width of the opening of a supplemental hopper leading to the passage in which the material is crushed.

A further object is to provide a yieldably 15 and universally mounted automatically operating feeding device adapted to alternately increase and diminish the opening of a supplemental hopper leading to the passage in which the material is crushed.

20 A still further object is to provide a feeding device which is automatically operated by the gyrations imparted to the crusher head shaft, to adapt said feeding device to alternately increase and decrease the width of the opening 25 of a supplemental hopper leading to the passage in which the material is crushed.

With the above primary object and other incidental objects in view, the invention consists of the devices and parts, or the equivalents thereof, as hereinafter more fully set forth.

In the accompanying drawings,

Fig. 1 is a vertical sectional view of a crusher equipped with my invention; and

Fig. 2 is a plan view thereof.

I have shown the invention in connection with the form of crusher illustrated in the accompanying drawings, although it will be understood that the invention is applicable 40 to any form of crushing machine wherein provision is made for rocking or tilting the feeding device.

The frame of the machine in connection with which the invention is shown, consists 45 of a lower section 3 and an upper section 4 suitably connected together.

Within the lower section 3 is a bearing sleeve 5, the upper end of which extends a slight distance into the upper section 4 of the 50 frame. The lower end of this sleeve is sup-

ported upon and secured to a plate 6 mounted in the lower portion of the frame.

Surrounding the lower end of the sleeve and keyed thereto is a beveled gear 7.

A horizontal drive shaft 8 has its bearings 55 in the lower portion of the frame member 3, and carries at its inner end a bevel pinion 9, which meshes with the bevel gear 7. In this manner, rotation is imparted to the sleeve 5.

The bore of the sleeve 5 is arranged eccentrically, and within the bore is disposed a vertical shaft 10 which extends upwardly into the upper frame member 4, and carries a conical crushing head 11. 60

Surrounding the crusher head, and spaced 65 a desired distance therefrom, is an outer coacting crushing jaw or member 12, said jaw having its inner surface inclined in a direction to form, in connection with the inclined surface of the crushing head, an outwardly 70 flaring and downwardly converging passage 13, said passage leading to a discharge chamber 14.

The machine is surmounted by a top plate 15, having a large central opening 16. This 75 plate is provided with a depending flange or rim 17 which surrounds the outer edge of the upper end of the upper frame member 4.

The particular machine illustrated, discloses means for permitting of a movement 80 of the outer crushing member, whereby the passage in which the material is crushed may be increased in width, to counteract for any clogging, but as this feature will form the subject matter of a separate application for 85 patent, it will be referred to herein only in a more or less general way.

It will be seen that bolts 18 pass freely through the top plate 15, and have their lower ends threaded, said threaded lower ends 90 entering threaded recesses in the top portion 4 of the frame. A coiled spring 19 surrounds each of these bolts, the lower end of said spring bearing against the upper surface of the top plate 15, and the upper end thereof bearing against a plate 20 movably mounted on each bolt. Nuts 21—21 are turned onto the upper threaded end of each bolt, and when these nuts are turned downwardly, the plate 20 is thereby forced down- 95 100

wardly, and compresses the spring, and of course increases the compression exerted by said spring. When the nuts are turned in the opposite direction, of course the tension of the spring is decreased.

It will be evident that the coil springs 19 act upon the top plate 15, and said top plate, in turn, bears against the outer crushing member or jaw 12, with the result that the said outer crushing jaw is normally held in the position shown in Figure 1 of the drawings. If, however, the passage in which the material is crushed, becomes clogged by overloading, or if the crushing jaws fail to crush the material passing through the passage, then the outer crushing member or jaw by reason of the pressure exerted thereon will be raised upwardly, and also forced laterally slightly. With the up movement of this crushing jaw, the top plate 15 is raised against the contrary force exerted by the coiled springs. In this way, the passage in which the material is crushed, is widened, and the clogging material thereby permitted to pass therefrom, and as the material flows from the passage, the coiled springs recoil, which acts to force the top plate 15, and the outer crushing jaw, downwardly, and to normal position.

A description will now be given of the improved feeding mechanism with which this application is particularly concerned.

It will be seen that a bolt 22 extends upwardly from the vertical shaft 10. This bolt is threaded for the greater part of its length, and the threads at the lower portion enter a threaded recess formed in the shaft 10. Also turning on the threads of the bolt is a nut 23 which is adapted to be turned down against a cap 24 surmounting the upper end of the shaft, and provided with an opening through which the bolt freely passes. This cap 24 bears against the upper end of the conical crusher head. A lock nut 25 also turns on the threads of the bolt 22 and against the nut 23, so as to lock the parts together.

The unthreaded portion of the bolt 22 which projects above the lock nut 25, carries a plate or disk 26, preferably of approximately conical shape, and provided at different points of its inclined surface with recesses 27 (preferably four in number) which form seats for the inner ends of coiled springs 28, said springs extending from the plate upwardly at an incline, and bearing at their outer ends against the inner surface of a cone-shaped feed regulating device 29. A main hopper 30 is disposed within the opening 16 of the top plate 15, and is secured at its lower end to the framework. This hopper is provided with an opening in its top, through which extends a supplemental hopper 31, the upper end of the supplemental hopper being flanged, and the flange secured

to the top of the main housing by means of bolts 32.

A bar 33 extends across the inlet mouth of the supplemental hopper and passing through an opening in this bar is a vertical rod 34, the upper end of which is threaded. A nut 35 is turned downwardly on the threads against the upper side of this bar and another nut 36 is turned upwardly on the threads against the underside of said bar, whereby the rod is firmly clamped in its depending position. The lower end of the rod passes freely through an opening 37 in the top of the cone shaped feed regulating device 29, and the lower extremity of said rod is enlarged and rounded, as indicated by the numeral 38, to fit beneath and conform to the under surface of the feed regulating device.

Also mounted on the rod 34 above the feed regulating device is a plate 39, the under surface of which is concave in form to fit the correspondingly shaped upper surface of the feed regulating device.

By the construction and arrangement just described, it is obvious that a universal joint movement is formed between the rod 34 and the feed regulator.

In the use of the invention, the material to be crushed is fed through the inlet end of the supplemental hopper and discharges from the lower open discharge end thereof onto the feed regulator 29. The material will slide down the inclined or sloping surface of the feed regulator and enter the main hopper, and will pass through the lower open end of said main hopper into the passage 13, where it is crushed by the action of the two crushing jaws.

It frequently happens that the material is fed into a hopper either too rapidly or unequally, so as to cause an overloading of the material in the passage 13, and consequent clogging of said passage and the preventing of the crushing jaws accomplishing their work. To regulate the feed, I have provided the universally mounted and yieldable feed regulating device 29 hereinbefore specifically described.

Furthermore, the material is frequently fed into a hopper, such as the main hopper 30, through a spout, and this naturally causes the material to accumulate in the hopper to a greater extent at the point of exit from the spout than at other points, and consequently prevents an even feed of the material to be crushed into the passageway 13. My improved feed regulator also obviates this. A gyratory movement is imparted to this feed regulator, and consequently even though the material is introduced into the supplemental hopper through a spout, yet the tilting of the feed regulator will cause an even distribution of the material into the main hopper.

It will also be seen that by the provision of

the coiled springs 28, the feed regulator is susceptible to a yielding motion, which in many instances, will be found very desirable. While I have disclosed the coiled springs as located between the plate 26 and the underside of the feed regulating device 29, yet I do not wish to be understood as confining myself to this particular location of said springs, inasmuch as they may be disposed at any other convenient point that will enable them to properly act on the feed regulating device.

In the accompanying drawing, the gyroscopic movement is imparted to the feed regulator 29, by reason of the connection formed between the vertical shaft 10, and the feed regulator by the rod 22, the plate 26 and the spring 28. Of course a gyroscopic movement is imparted to the vertical shaft 10, and its crushing head 11 by reason of the fact that said shaft is mounted eccentrically in the bore of the sleeve 5.

It will be understood, however, that the invention is not limited to this particular means for imparting the desired movement to the feed regulator, as any other mechanism may be employed whereby the feed regulating device may be freely moved or gyrated on its universal joint connection.

Attention is also directed to the fact that while the invention is particularly desirable for use in connection with crushing machines, yet the improved feed regulating mechanism may be employed in connection with various machines wherein material is introduced through a hopper, and wherein it is desirable to maintain an even distribution of the material passing through the discharge opening of the hopper.

A very important feature of my invention is the provision of means whereby an adjustment vertically of the feed regulator is made possible. The preferred means for this purpose consists of the nuts 35 and 36, which, when turned, will cause an up or down movement of the rod 34, and consequently of the feed regulator 29, depending upon the direction of turning of said nuts.

Of course, when the adjustment above set forth is made, it is likewise necessary to adjust the plate or collar 26. As one means for accomplishing this last referred to adjustment, a washer 40 is employed which is mounted on the bolt 22, and interposed between the nut 25 and plate 26. As the adjustment of the feed regulator 29 is altered, a thicker or thinner washer, as may be required, is substituted.

What I claim as my invention is:

1. In a feeding device for crushers and the like, the combination of a frame provided with a discharge opening for the material, a main hopper or housing mounted on the frame and communicating with the discharge opening of said frame, a supplemental hop-

per mounted to discharge into the main hopper or housing, a universally mounted feed regulating device mounted below the discharge opening of the supplemental hopper, and means acting upon the feed regulating device to cause alternate rocking or tilting of said device in different directions on its universal mounting, to thereby alternately increase and decrease the width of the discharge opening of the feed regulating device at different points. 75

2. In a feeding device for crushers and the like, the combination of a frame provided with an opening for the discharge of the material, a main hopper or housing mounted on the frame and communicating with said opening, a supplemental hopper mounted to discharge into the main hopper or housing, a spring-pressed or cushioned feed regulating device mounted movably below the discharge opening of the supplemental hopper, and means for alternately rocking or tilting said feed regulating device in different directions to thereby alternately increase and decrease the width of the discharge opening of the supplemental hopper at different points. 90

3. In a feeding device for crushers and the like, the combination of a frame provided with an opening for the discharge of the material, a main hopper or housing mounted on the frame, and communicating with said opening, a supplemental hopper mounted to discharge into the main hopper or housing, a spring-pressed or cushioned universally mounted feed regulating device, and disposed below the discharge opening of the supplemental hopper, and means acting on the feed regulating device to cause alternate rocking or tilting of said device in different directions on its universal mounting, to thereby alternately increase and decrease the width of the discharge opening of the feed regulating device at different points. 105

4. In a feeding device for crushers and the like, the combination of a frame provided with an opening for the discharge of the material, a main hopper or housing mounted on the frame and communicating with said opening, a supplemental hopper mounted to discharge into the main hopper or housing, a bar extending across the mouth of the supplemental hopper, a rod connected to said bar and depending therefrom, the lower end of said rod being enlarged and rounded, a cone shaped feed regulating device mounted on the rod, the under surface thereof resting upon the enlarged rounded lower end of the rod, and means for alternately rocking or tilting said feed regulating device in different directions, to thereby alternately increase and decrease the width of the discharge opening of the supplemental hopper at different points. 115

5. In a feeding device for crushers and the like, the combination of a frame provided with a discharge opening for the material, a main hopper or housing mounted on the frame and communicating with the discharge opening of said frame, a supplemental hop-

with an opening for the discharge of the material, a main hopper or housing mounted on the frame and communicating with said opening, a supplemental hopper mounted to discharge into the main hopper or housing, a bar extending across the mouth of the supplemental hopper, a rod connected to said bar and depending therefrom, said rod provided with a lower enlarged and rounded end, a cone-shaped feed regulating device mounted on the rod above the lower enlarged rounded end of said rod and adapted to rest upon said enlarged end, a block fitted to the rod and provided with a concave under surface against which the upper rounded apex of the cone-shaped feed regulator is adapted to bear, and means for alternately rocking or tilting the feed regulating device in different directions, to thereby alternately increase and decrease the width of the discharge opening of the supplemental hopper at different points.

6. In a feeding device for crushers and the like, the combination of a frame having an opening for the discharge of the material, a gyratory shaft mounted in said frame, a main hopper or housing mounted on the frame and communicating with said opening, a supplemental hopper mounted to discharge into the main hopper or housing, a bar extending across the mouth of the supplemental hopper, a rod connected to and depending from said bar, the lower end of said rod being enlarged and rounded, a cone-shaped feed regulating device mounted on the rod and resting on the rounded lower end of the rod, a plate mounted on the rod and having a concave under surface against which the rounded apex of the cone-shaped feeding device bears, and a connection between the gyratory shaft and the feed regulating device, whereby the gyrations of the shaft are imparted to the feed regulating device, to thereby cause said device to alternately increase and decrease the width of the discharge opening of the supplemental hopper at different points.

7. In a feeding device for crushers and the like, the combination of a frame provided with an opening for the discharge of the material, a gyratory shaft mounted in said frame, a main hopper or housing mounted on the frame and communicating with said opening, a supplemental hopper mounted to discharge into the main hopper or housing, a bar extending across the mouth of the supplemental hopper, a rod secured to and depending from said bar, the said rod provided with a lower enlarged rounded end, a cone-shaped feed regulating device mounted on the rod and resting upon the rounded lower end of said rod, a plate also mounted on the rod and provided with a concave under surface against which the rounded apex of the feed regulating device bears, a rod extending upwardly from the gyratory shaft, a plate carried by said rod, and coiled springs inter-

posed between said plate and the under side of the cone-shaped feed regulating device.

8. In a feeding device for crushers and the like, the combination of a frame provided with an opening for the discharge of the material, a main hopper or housing mounted on the frame and communicating with said opening, a supplemental hopper mounted to discharge into the main hopper or housing, a feed regulating device movably mounted below the opening of the supplemental hopper, means for vertically adjusting the feed regulating device, a gyratory shaft mounted in the frame, a rod extending upwardly from the gyratory shaft, a plate carried by said rod, a spring mechanism interposed between the plate and the feed regulating device, and means for adjusting the said plate vertically on the rod.

9. In a feeding device for crushers and the like, the combination of a frame having means for acting on the material passing through the machine, a hopper leading to the means which acts on the material, a universally mounted feed regulating device mounted below the discharge opening of the hopper, and means acting upon the feed regulating device to cause alternate rocking or tilting of said device in different directions on its universal mounting, to thereby alternately increase and decrease the width of the discharge opening of said hopper at different points.

10. In a feeding device for crushers and the like, the combination of a frame having means for acting on the material passing through the machine, a hopper leading to the means which acts on the material, a spring-pressed or cushioned feed regulating device mounted movably below the discharge opening of the hopper, and means for alternately rocking or tilting said feed regulating device in different directions to thereby alternately increase and decrease the width of the discharge opening of the hopper at different points.

11. In a feeding device for crushers and the like, the combination of a frame having means for acting on the material passing through the machine, a hopper leading to the means which acts on the material, a spring-pressed or cushioned universally mounted feed regulating device disposed below the discharge opening of the hopper, and means acting on the feed regulating device to cause alternate rocking or tilting of said device in different directions on its universal mounting, to thereby alternately increase and decrease the width of the discharge opening of the hopper at different points.

12. In a feeding device for crushers and the like, the combination of a frame having means adapted to act on the material passing through the machine, a hopper leading to the means which acts on the material, a feed regulating device movably connected to the

frame and positioned closely below and extending into the opening of the hopper, and means forming part of the rotary crushing member for alternately rocking or tilting said feed regulating device in different directions to thereby alternately open and substantially close portions of the discharge opening of said hopper.

13. In a crusher having a frame provided with a concave crushing member and a crusher head, a feeding means therefor, comprising a material conduit carried by the frame and positioned above the crusher head, a feed controlling member pivotally and loosely supported from the frame and extending beneath the conduit, and means carried by the crusher head for imparting a rocking movement to the controlling member.

14. In a crusher having a frame provided with a concave crusher member and a crusher head, a feeding means therefor, comprising a material conduit carried by the frame and positioned above crusher head, a feed controlling member pivotally and loosely supported from the frame and extending beneath the conduit, said crusher head turning in an eccentric path in the concave member, and a connection between the crusher head and the controlling member for imparting a gyratory movement to the controlling member.

15. In a crusher having a frame provided with a concave crusher member and crusher head, a feeding means therefor, comprising a material conduit carried by the frame and positioned above the crusher head, a feed controlling member pivotally and loosely supported from the frame and extending beneath the conduit, said crusher head turning in an eccentric path in the concave member, and a yielding connection between the crusher head and controlling member for imparting a gyratory movement to the controlling member.

In testimony whereof, I affix my signature.
CHARLES F. SMITH.
